UNITED STATES PATENT OFFICE.

GEORGE A. BIRCH, OF EAST GREENBUSH, NEW YORK.

SNOW-SCRAPER.

SPECIFICATION forming part of Letters Patent No. 293,620, dated February 19, 1884.

Application filed January 11, 1884. (No model.)

To all whom it may concern:

Be it known that I, GEORGE A. BIRCH, of East Greenbush, in the county of Rensselaer and State of New York, have invented certain 5 new and useful Improvements in Snow-Scrapers, of which the following is a specification.

My invention relates to improvements in that class of snow-scrapers that is known as the "fire-board" scraper, and is used for the 10 purpose of removing snow from a field of ice preparatory to the operation of harvesting the ice for storing; and the object of my improvements is to increase the effectiveness of the apparatus in the operations of scraping snow 15 from the surface of the ice, and facilitating the operations of transporting and dumping the snow that is collected on the scraper. I attain this object by means of the construction 20 illustrated in the accompanying drawings, which form part of this specification, and in which—

Figure 1 is a side elevation of my scraper with the several parts in position for the 25 operation of scraping; Fig. 2, a plan view of the same; Fig. 3, a vertical section at line $x-x$ of Fig. 2; and Fig. 4 an end elevation of a modified construction of the face-board of the scraper.

As represented in the drawings, A is the 30 face-board of the scraper, which may be made of any required size. Said face-board is beveled on the under side of its foremost edge, and is provided at that point with a metallic scraping-shoe, a. End pieces, a', and a back piece, a'', are secured to the upper surface of 35 said face-board for the purpose of adapting it for carrying an accumulated load of snow; and the runners B (or, when preferred, the wheels B', as shown in Fig. 4) are secured to the under side of said face-board for the 40 purpose of facilitating the removal of the apparatus from place to place while carrying a load of snow. The face-board A is pivoted, by means of pins or bolts c inserted through the 45 end pieces, a', to a pair of independent runners, C, on which the apparatus is carried from place to place while unloaded. The runners C are connected together by means of a cross-bar, c', which is secured to the forward 50 ends of them.

D is a pole, to which horses are attached in the usual manner for the purpose of drawing the apparatus. Said pole is provided with branching arms d, which engage with joint-plates a³, secured to the upper surface of the 55 face-board A for the purpose of forming a flexible joint between said pole and the face-board. A stay-piece, d', that is secured to the upper side of the pole D and arms d, gives stability to the latter. A longitudinal 60 stirrup, E, is fixed to the under side of the pole D, and passes underneath the cross-bar c' in such manner that, while the said cross-bar has ample room to move freely without restricting the free movement of the runners 65 C, the latter will be prevented from being thrown over out of their places.

F is a hand-lever for overturning the face-board A. Said lever is pivoted to a bracket, d'', secured at or near the innermost end of the 70 pole D, and extends rearwardly through a slot, a⁴, formed in the afterpart of the face-board and its back-piece. Said lever has in its lower edge a notch, f, which engages with a catch-bar, a⁵, fixed across the slot a⁴ in such 75 manner that the lever F will retain the face-board A in its required angular position while it is performing its work in scraping. The bracket d'' is provided with several holes for receiving the pin f', whereby the lever F is 80 attached to said bracket, and, by shifting said pin into the different holes of said bracket, the angularity of the face-board A may be readily changed as occasion requires.

G is a roller arranged in the upper part of 85 the slot a⁴ for the purpose of facilitating the operation of overturning the face-board A by means of the hand-lever F in the manner hereinafter described.

My scraper operates in the following manner: The parts being in the positions shown by the full lines of Fig. 1, and the horses being attached to the pole D, the scraper is drawn forward until a sufficient load of snow is collected on the face-board A. Then the lever F 90 is raised far enough to disengage its notch f from the catch-bar a⁵, thereby releasing the hold of said lever from the face-board A, and permitting the latter to drop into the position indicated by the dotted lines of Fig. 1, where 100

the weight of it and its load will bear entirely upon the runners B, and while in this condition it can easily be drawn to the dumping-ground. Thereupon the lever F is raised up, 5 and by its continued movement the face-board A is thrown over into the position indicated by the dotted lines of Fig. 3, to effect the dumping of the load therefrom. In effecting the dumping movement of the face-board A, the 10 lever F will bear against the roller G, whereby the friction will be greatly lessened. While the parts are in the positions indicated by the dotted lines of Fig. 3, wherein the whole weight of the apparatus will be borne upon 15 the runners C, and while in this position it will be drawn back to the ice-field, and then the face-board A will be restored to the position first described, on attaining which the notch f will re-engage with the catch-bar a' 20 and the apparatus will be ready for a repetition of the operation described.

When preferred the runners C may be dispensed with, and when so constructed the weight of the apparatus, when the face-board

A is turned over to effect the dumping, will 25 rest upon the end pieces, a', which will then serve as runners.

I claim as my invention—

1. In a snow-scraper, the combination, with 30 a face-board, A, and tongue D, hinged to said face-board, and provided with a lever, F, adapted to engage with the face-board A, substantially as described, of the runners C, pivotally connected to the face-board A, all being constructed and arranged to operate 35 substantially as herein specified.

2. In a snow-scraper, the combination, with 40 a face-board, A, provided with the runners B, or their described equivalents, of the tongue D, hinged to said face-board, and a lever, F, fulcrumed to said tongue and adapted to secure the face-board A in its angular position, and to effect the dumping movement of said face-board, substantially as herein specified.

GEORGE A. BIRCH.
